[57] CLAIM

The ornamental design for my combined housing and
handle for a lifting system, as shown and described.

DESCRIPTION

FIG. 1 is a top plan view of a combined housing and
handle for a lifting system showing my new design;
FIG. 2 is a bottom plan view;

FIG. 3 is a front elevational view thereof;

FIG. 4 is a right side elevational view thereof;

FIG. 5 is a left side elevational view thereof; and,

FIG. 6 is a prospective view taken from the top rear and
right sides thereof.

FIG. 1

FIG. 2

FIG. 3**FIG. 4****FIG.5**

FIG. 6
